US0D1077790S

(12) **United States Design Patent** (10) **Patent No.:** **US D1,077,790 S**
(45) **Date of Patent:** **** Jun. 3, 2025**

(54) **MOBILE PHONE HOLDER**

(71) Applicant: **eMoMo Technology Co., Ltd.**, Baoan (CN)

(72) Inventors: **Wenji Tang**, Shenzhen (CN); **Zhigang Wang**, Qiyang (CN); **Qishuang Lu**, Dengzhou (CN)

(73) Assignee: **eMoMo Technology Co., Ltd.**, Baoan (CN)

(**) Term: **15 Years**

(21) Appl. No.: **29/729,370**

(22) Filed: **Mar. 26, 2020**

(30) **Foreign Application Priority Data**

Sep. 29, 2019 (CN) 201930539030.3

(51) **LOC (15) Cl.** **14-06**

(57) **CLAIM**

The ornamental design for a mobile phone holder, as shown and described.

DESCRIPTION

FIG. 1 is a top rear perspective view of a first embodiment of a mobile phone holder showing a first configuration of a holder portion in broken lines, showing our new design; FIG. 2 is a bottom front perspective view thereof; FIG. 3 is a top plan view thereof; FIG. 4 is a bottom plan view thereof; FIG. 5 is a left side elevation view thereof; FIG. 6 is a right side elevation view thereof; FIG. 7 is a front elevation view thereof; FIG. 8 is a rear elevation view thereof; FIG. 9 is a top rear perspective view of the first embodiment of the mobile phone holder showing a second configuration of a holder portion in broken lines, showing our new design; FIG. 10 is a bottom front perspective view thereof; FIG. 11 is a top plan view thereof; FIG. 12 is a bottom plan view thereof; FIG. 13 is a left side elevation view thereof; FIG. 14 is a right side elevation view thereof; FIG. 15 is a front elevation view thereof; FIG. 16 is a rear elevation view thereof; FIG. 17 is a top rear perspective view of a second embodiment of the mobile phone holder showing a first configuration of a holder portion in broken lines, showing our new design; FIG. 18 is a bottom front perspective view thereof; FIG. 19 is a top plan view thereof; FIG. 20 is a bottom plan view thereof; FIG. 21 is a left side elevation view thereof; FIG. 22 is a right side elevation view thereof; FIG. 23 is a front elevation view thereof; FIG. 24 is a rear elevation view thereof; FIG. 25 is a top rear perspective view of the second embodiment of the mobile phone holder showing a second configuration of a holder portion in broken lines, showing our new design; FIG. 26 is a bottom front perspective view thereof; FIG. 27 is a top plan view thereof; FIG. 28 is a bottom plan view thereof; FIG. 29 is a left side elevation view thereof; FIG. 30 is a right side elevation view thereof; FIG. 31 is a front elevation view thereof; and, FIG. 32 is a rear elevation view thereof.
The dash-dash broken lines depict elements that form no part of the claimed design. The surfaces directly adjacent to portions of the design shown in dash-dash broken lines in FIGS. 2, 4, 10, 12, 18, 20, 26, and 28 do not form part of the claimed design. The broken lines showing a holder portion of the Mobile Phone Holder depicts environment that forms no part of the claimed design. All other broken lines are directed to portions of the article which form no part the claimed design.
